CLAIM

The ornamental design for a combined firearm suppressor core and tube, as shown and described.

DESCRIPTION

FIG. 1 is a top, front, right side perspective view of a combined firearm suppressor core and tube in accordance

with our new design, the combined firearm suppressor core and tube being in an assembled configuration, and the firearm suppressor core being received in the tube; FIG. 2 is a top, rear, left side perspective view of the combined firearm suppressor core and tube of FIG. 1; FIG. 3 is a top view of the combined firearm suppressor core and tube of FIG. 1; FIG. 4 is a bottom view of the combined firearm suppressor core and tube of FIG. 1; FIG. 5 is a front view of the combined firearm suppressor core and tube of FIG. 1; FIG. 6 is a rear view of the combined firearm suppressor core and tube of FIG. 1; FIG. 7 is a left side view of the combined firearm suppressor core and tube of FIG. 1; FIG. 8 is a right side view of the combined firearm suppressor core and tube of FIG. 1; FIG. 9 is a top, front, left side perspective view of the combined firearm suppressor core and tube of FIG. 1; FIG. 10 is a bottom, rear, right side perspective view of the combined firearm suppressor core and tube of FIG. 1; FIG. 11 is a top, rear, right side perspective view of the combined firearm suppressor core and tube of FIG. 1; FIG. 12 is a cross-sectional view of the combined firearm suppressor core and tube of FIG. 1, along line 12-12; FIG. 13 is a cross-sectional view of the combined firearm suppressor core and tube of FIG. 1, along line 13-13; FIG. 14 is a top, front, right side perspective view of the combined firearm suppressor core and tube of FIG. 1, the combined firearm suppressor core and tube being in a

disassembled configuration, the firearm suppressor core being removed from the tube, and being positioned adjacent to the tube;

FIG. 15 is a top, rear, left side perspective view of the combined firearm suppressor core and tube of FIG. 14;

FIG. 16 is a top view of the combined firearm suppressor core and tube of FIG. 14;

FIG. 17 is a bottom view of the combined firearm suppressor core and tube of FIG. 14;

FIG. 18 is a front view of the combined firearm suppressor core and tube of FIG. 14;

FIG. 19 is a rear view of the combined firearm suppressor core and tube of FIG. 14;

FIG. 20 is a left side view of the combined firearm suppressor core and tube of FIG. 14;

FIG. 21 is a right side view of the combined firearm suppressor core and tube of FIG. 14;

FIG. 22 is a top, front, left side perspective view of the combined firearm suppressor core and tube of FIG. 14;

FIG. 23 is a bottom, rear, right side perspective view of the combined firearm suppressor core and tube of FIG. 14;

FIG. 24 is a top, rear, right side perspective view of the combined firearm suppressor core and tube of FIG. 14;

FIG. 25 is a cross-sectional view of the combined firearm suppressor core and tube of FIG. 14, along line 25-25; and,

FIG. 26 is a cross-sectional view of the combined firearm suppressor core and tube of FIG. 18, along line 26-26. The broken lines immediately adjacent the shaded areas represent the bounds of the claimed design. All broken lines are directed to environment and are for illustrative purposes only and form no part of the claimed design.
